MACHINE FOR OPERATING ON SHOE PARTS

Charles E. Hood, Lynn, Mass., assignor to United
Shoe Machinery Corporation, Paterson, N. J.,
a corporation of New Jersey

Application December 12, 1934, Serial No. 757,181

14 Claims. (Cl. 12—17)

This invention relates to gaging mechanisms and is herein illustrated and described as embodied in a skiving machine of the type illustrated in United States Letters Patent No. 1,382,689, granted June 28, 1921, upon the application of W. C. Stewart. The machine disclosed in that patent is used for skiving the shank portions of outsoles at each side of the soles. It is provided with a matrix roll and a feed roll between which the soles are fed past a skiving knife. The feed roll presses the central portion of the sole into a recess which is formed in the matrix roll, and the shape of this recess controls the deformation of the sole while it is being fed and thus determines the position and extent of the cuts which are made by the skiving knife. In order properly to position the sole in relation to the recess of the matrix roll the machine is provided with a gage mechanism for centering the forepart of the sole and also with a gage mechanism for centering the heel end of the sole. Each of these centering gage mechanisms consists of a pair of pivotally mounted gage members which contact with the opposite lateral edges of the sole and which are urged together by a spring. These members are forced apart when a sole is entered between them and their movements are coordinated by a pair of gear segments which are in mesh with each other, each of the gear segments being secured to one of the gage members. The gear segments of the above-identified patented construction have equal pitch diameters and it is evident that regardless of the width of the portion of the sole which is entered between the gage members the common center line between the gage members will always occupy a fixed position.

It is an object of the present invention to provide an improved gaging mechanism of the type above referred to.

When soles of different sizes but of the same style are presented in properly gaged relation to the recess of the matrix roll, the difference in size presents a greater variation on the inner edge of the forepart of the sole than upon the outer edge. It is therefore desirable to provide for a greater movement of the forepart gage member which contacts with the inner edge of the sole than for the member which contacts with the outer edge. In accordance with a feature of the invention, and in order to provide for greater movement of one of the members than the other, the gear which is secured to one gage member has a greater pitch diameter than the gear which is secured to the other

gage member. With this construction the midpoint between the gage members, or, as it is frequently called, the common center line, will not occupy a fixed position but will be displaced in accordance with the degree of separation of the gage members when a work piece is inserted between them. Such shifting of the common center line in most cases is sufficient to adapt the forepart centering gage mechanism to soles of different size without the need of lateral bodily adjustment of the gage mechanism.

Skiving machines of the type under consideration are frequently used for operating upon block soles. The outline of such a sole is arbitrary and has no necessary relation to the outline of what eventually will be the finished or rounded sole. For the same size and style of sole there may be considerable variation in the outlines of different lots of block soles. Such variations of outline usually involve a shifting of the center line of the block sole with reference to the true center line of the sole, that is, the center line of the sole in its ultimate rounded form. It is desirable, therefore, to provide for adjusting the centering gage mechanism to enable the operator properly to position a block sole in relation to the matrix recess in such a manner that the sole will be skived in proper relation to what eventually will become its rounded outline. With this purpose in view means are provided for adjusting the position of one of the gage members independently of the other to change the position of the common center line. In the illustrated construction, as has already been pointed out, the movements of the gage members are coordinated by intermeshing gears. In accordance with a feature of the invention, one of the gage members is pivotally mounted in coaxial relation to one of the gears and is secured to that gear by a device which provides for the angular adjustment of the gear and of the gage member relatively to each other about the pivotal mounting. The other gage member is directly carried by the gear which controls its movement. By reason of the provision for relative angular adjustment between one of the gage members and its coordinating gear, that gage member can readily be adjusted independently of the other gage member.

A further feature of the invention consists in the provision of an extension to each of the forepart gaging members to enable the forepart gaging members to accommodate soles of unusual length. Such extensions partly embrace the matrix roll and enable the gaging members to

contact with the work on both sides of the bite of the rolls. Provision is made for readily detaching these extensions when they are not needed.

5 In addition to the features of invention above referred to the present invention also consists in certain features of construction and combinations of parts hereinafter described and claimed, the advantages of which will be obvious to those skilled in the art from the following 10 description.

The various features of the invention are illustrated in the accompanying drawings, in which

15 Fig. 1 is a vertical sectional view, taken on the line I—I of Fig. 2, of a portion of a shank skiving machine embody the present invention;

Fig. 2 is a plan view of the parts shown in Fig. 1; and

20 Fig. 3 is a view in perspective of a portion of the machine.

The invention is illustrated as embodied in a shank skiving machine of the type disclosed in Letters Patent No. 1,382,689 above referred to. This machine, as shown in Fig. 1, is provided 25 with a matrix roll 10 mounted upon a shaft 12, and also with a feed roll comprising a plurality of serrated disks 14 mounted upon a shaft 16. The matrix roll shaft 12 is journaled at its ends in bearing blocks 18 each of which is slidably 30 mounted for vertical adjustment between a pair of forks 20 extending upwardly from a frame 22. The feed roll shaft 16 is journaled at its ends in a pair of hanger arms 24 which are pivotally mounted upon pins 26 secured in the frame 22. 35 The hanger arms 24 are urged upwardly by spring pressure to a limited position determined by adjustable stops 25 which engage extensions 27 on the hanger arms. Extending close to the bite of the matrix and feed rolls is a skiving 40 knife 26 which is mounted upon a bed plate 28 secured at its ends in the frame 22. Slidably mounted in a carriage 30 is a block 32. The block 32 may be adjusted in the carriage 30 toward and from the matrix and feed rolls by a 45 mechanism indicated generally by the numeral 34. A back gage 36 for engaging the rear end of the sole is slidably mounted upon the block 32 for adjustment toward and from the matrix and feed rolls and is secured in adjusted position 50 relatively to the block 32 by a screw 38. The block 32 also carries a heel centering gage mechanism which will presently be described. Extending from each end of the frame 22 is a bar 55 40 upon which is secured a block 42 which carries a fore-part centering gage mechanism presently to be described.

A sole blank herein shown as a block sole S is shown supported by the carriage 30 with the ball portion of the blank extending between the 60 matrix roll and the feed roll in readiness to be acted upon by the skiving knife. The sole blank is located lengthwise with reference to the matrix roll by means of the back gage 36. A guide plate 65 37 prevents the heel end of the sole, as it is being inserted, from riding up over the back gage. The sole blank is positioned laterally with respect to the matrix roll by the above-mentioned centering gages. The matrix and pressure rolls cooperate 70 to feed the sole blank past the skiving knife, while the matrix acts upon the opposite margins of the shank portion of the blank to offset these portions from the plane of the sole, thereby deflecting them into the plane of the skiving knife 75 so that they will be reduced or beveled as the

sole blank is fed past the knife. The knife cuts from the ball line toward the breast line.

As shown in Fig. 2, the machine is arranged to operate simultaneously upon a right and a left sole, the sole S already mentioned being a right sole (which is seen inverted in Fig. 2) while a left sole is indicated by the reference character S'. The matrix roll 10 is designed to operate upon the right sole S, and the shaft 12 is provided with an additional matrix roll 10' for operating upon the left sole S'. As also shown in Fig. 2, separate sets of gaging mechanisms are provided for right and left soles.

The machine, as so far described, is substantially the same in construction and arrangement, 15 and has substantially the same mode of operation as the machine disclosed in the above-mentioned Letters Patent No. 1,382,689 and reference may be had to that patent for details of construction and operation not fully set forth 20 herein.

In Fig. 2 the outline of the right block sole is indicated by the full line S, while the outline of what is eventually to become the finished or rounded right sole is indicated by the broken line 25 R. The outline of the left block sole is indicated by the full line S', and the outline to which the left block sole eventually will be rounded is indicated by the broken line R'. For any given size and style of shoe the outline R or R' of the 30 rounded sole will always be the same, and it is in relation to this outline that the sole blank should be gaged with reference to the matrix roll. However, the outline S or S' of the block sole has no necessary relation to the outline R 35 or R' of the finished or rounded sole, and for any one style and size of sole there may be considerable variation in the outline S or S'. It is therefore necessary to center the block sole, however arbitrary may be its outline, with reference 40 to what will eventually be the outline of the finished sole. The gaging mechanism however must contact with the tangible edges of the actual block sole. In order to enable the operator to allow for variations in the outline of the block 45 sole, the illustrated machine is provided with an improved form of centering gages.

The heel centering gages are alike for both right and left soles, and the same reference characters will be used in describing corresponding 50 parts of each of them. Each heel centering gage comprises a pair of arms 44 and 46, each of which arms has a work engaging portion 48 at its forward end. The work engaging portions 48 engage the opposite edges respectively of the heel portion 55 of the block sole S or S'. The arm 44 is pivotally mounted upon a pin 50 and has a bell crank extension 52 upon which is formed a gear segment 54. The arm 46 is provided at its rear end with a pair of ears 56 by which it is pivotally mounted upon a pin 58. The pins 50 and 58 are secured in the gage block 32. Separate gage blocks 32 are provided for the heel gages for right and left soles. Pivotally mounted upon the pin 58 between the ears 56 is an arm 60 carrying a gear segment 62 65 which is in mesh with the gear segment 54. The arm 60 has a bell crank extension 64. Upon the arm 64 is pivotally mounted a block having a pair of upstanding ears 66. Rotatably mounted upon an extension of the arm 46 is an upstanding 70 pin 68. A screw 70 which is threaded transversely through the pin 68 has a shank portion which is journaled in the ears 66. A thrust collar 72 which is secured upon the shank of the screw 70 is retained between the ears 66 and thus holds 75

the screw 70 against axial movement relatively to the ears 66. The screw 70 is provided with a graduated head 74, and as the head 74 is turned it will be evident that the arm 46 will be swung about the pin 58, thereby varying its angular relation with respect to the gear segment 62. The mid-point between the work engaging portions 48 of the gage members will thus be shifted by a distance equal to half that of the displacement of the arm 46. In order to provide a definite setting for such adjustments, a pointer 76 is slidably mounted in the ears 66 and is secured in the pin 68. Scale markings are provided on the head 74, which cooperate with the pointer 76 to indicate the setting of the adjustment. A tension spring 78 having one end anchored in the gage block 32 and having its opposite end secured to the arm 52 urges the gage members 48 toward each other. A stop screw 80 which is threaded in a lug formed on the gage block 32 engages the arm 60 to limit the inward movement of the gages 48 under the influence of the spring 78. It will be evident that with the adjustment above described, the operator may position the heel end 25 of a block sole in a desired relation to the matrix regardless of any irregularity of outline of the block sole. Such irregularity may be compensated for by shifting the mid-point or common center line of the gage members as above described. This adjustment is useful also when operating upon rounded soles, inasmuch as it enables the operator to vary the common center line of the gage member to accommodate the varying swing of soles of different styles.

35 The centering gage mechanism for the forepart of the block sole S is mounted upon the gage block 42. The work engaging members which contact with the inner and outer edges of the block sole S are indicated in Fig. 2 by the reference-characters 82 and 84 respectively. The member 82 is pivotally mounted upon the outer end of an arm 86 which is fulcrumed upon a pin 88, and the member 84 is pivotally mounted upon the outer end of an arm 90 which is fulcrumed upon a pin 92. The pins 88 and 92 are secured to the gage block 42. The arm 90 carries a bell crank extension 94 upon the outer end of which is formed a gear segment 96. In mesh with the gear segment 96 is a gear segment 98 which is mounted for rotation about the pin 88. Integral with the gear segment 98 and extending oppositely therefrom beyond the fulcrum pin 88 is an arm 100 upon which is pivotally mounted a block having a pair of upstanding ears 102. Pivotally mounted in an extension of the arm 86 is an upstanding pin 104. A screw 106 is threaded transversely through the pin 104 and has an unthreaded shank portion journaled in the ears 102. A collar 108 which is secured upon the shank portion of the screw 106 between the ears 102 holds the screw against axial movement relatively to the ears 102. The screw 106 is provided with a graduated head 110. A pointer 112 is secured by a thumb-screw 113 (Fig. 1) in the pin 104 and is slidably mounted in the ears 102. The pointer 112 cooperates with scale markings upon the head 110, enabling the operator to obtain a desired setting of the forepart gage members in a manner similar to that described in connection with the heel centering gage members. As already stated, the work engaging members 82 and 84 of the forepart centering gage mechanism are pivotally mounted upon their respective arms. In order to insure parallel relation between the work engaging surfaces of the members 82 and

84 regardless of the setting of the gage mechanism, there is provided a plate 114 which is secured upon the pins 88 and 92 in fixed relation to the gage block 42. A link 116 has its ends pivotally connected to the gage member 82 and the plate 114 respectively, while another link 118 has its ends pivotally connected to the gage member 84 and the plate 114 respectively. The link 116 is always parallel to the line joining the axis of the pivot pin 88 to the axis of the pivotal connection between the arm 86 and the gage member 82, while the link 118 is always parallel to the line joining the axis of the pivot pin 92 to the pivotal connection between the arm 90 and the gage member 84. It is thus evident that regardless of the swinging movement of the arm 86, the gage member 82 will always occupy positions which are parallel to each other, and, likewise, regardless of the swinging movement of the arm 90 the gage member 84 will always occupy parallel positions. The working faces of the gage members 82 and 84 are substantially plane over the greater portions of their extent, the plane portion of each gage member being substantially normal to the axes of the matrix and feed rolls. The plane work engaging surfaces of the gage members 82 and 84 are therefore always parallel to each other and always extend in the direction of feed of the work. A tension spring 120 urges the arms 86 and 90 toward each other to cause the work engaging members 82 and 84 to contact with the respective edges of the forepart of the sole S. A stop screw 122 which is threaded in the gage block 42 engages the bell crank arm 94 to limit the inward movement of the gage members under the influence of the spring 120. A plate 123 for supporting the forepart of the sole is mounted on the plate 114.

It is desirable, once a sole has been inserted between the gage members 82 and 84, to prevent the swinging together of the gage members 82 and 84 as the sole is fed to the machine. To this end, there is formed upon the arm 86 a ratchet 124 which is engaged by one or another of a set of three pawls 126 pivotally mounted upon a pin 128 secured in the gage block 42. The points of the pawls 126 which engage the teeth of the ratchet 124 are staggered in relation to each other to obtain a more accurate setting than if a single pawl were relied upon. Mounted in the gage block 42 are three spring pressed plungers 130 which engage the tails 132 of the three pawls respectively to urge the pawls into engagement with the ratchet teeth. The direction of the ratchet teeth is such as to permit separation of the gage members 82 and 84 but to prevent closing of them. After a sole has been fed through the machine, the pawls 126 are automatically tripped by a lever 133 (Fig. 1) operated by mechanism similar to that disclosed in the above-mentioned Letters Patent No. 1,382,689.

It will be noted that the work engaging members 82 and 84 of the forepart centering gage mechanism contact with the respective edges of the sole S upon one side only of the bite of the matrix and feed rolls. It is sometimes desirable, however, in order to insure proper control of soles of unusual length to provide for contacting the sole on the opposite side of the bite of the matrix and feed rolls. To this end the gage member 82 is provided with an extension 134 which extends partly around the matrix roll 10 and has a work engaging surface 136 upon the opposite side of the matrix roll. The work engaging surface 136 lies in the same plane as the 75

plane portion of the work engaging member 82. The extension 134 is provided with a tongue 138 which is received between a pair of ears 140 extending from the work engaging member 82. A locking pin 142 having a knurled head, as shown in Fig. 2, extends through the ears 140 and the tongue 138 to secure the extension 134 to the member 82. The extension 134 is provided with a pair of shoulders 144 which engage the respective ends of the ears 140 to prevent rotation of the extension 134 about the pin 142. The pin 142 is normally held in locking position by a spring 146 which is anchored in the member 82 by a pin 148. The knurled head on the locking pin 142 facilitates withdrawal when removal or replacement of the extension 134 is desired. A similar extension 150 is provided upon the gage member 84, and the various parts of the extension 150 are numbered to correspond to similar parts on the extension 134.

The centering gage mechanism for the forepart of the block sole S' is mounted on a gage block 42' which is similar to the block 42 and which is similarly supported. All portions of the centering gage mechanism for the forepart of the block sole S' are similar to corresponding portions of the centering gage mechanism for the forepart of the block sole S and are similarly numbered. The two sets of gage mechanisms are identical, except for a right and left reversal to enable them to operate upon right and left soles. As seen in plan view (Fig. 2) either mechanism corresponds to a mirror image of the other.

35 It will be observed that when several sizes of soles of the same style are superimposed the larger sizes overlap the smaller sizes by a much greater margin at the inner edge of the shank than at the outer edge. That is, if a particular size of sole is properly positioned in relation to the matrix roll, then when a larger sized sole is inserted between the forepart gages, the inner gage member 82 must travel a greater distance than the outer gage member 84 in order properly to position the larger sized sole. While this is particularly true of rounded soles, it is also to some extent true of block soles, and, inasmuch as the illustrated machine is intended to be used for both types of soles, this consideration has been taken into account in the construction of the improved forepart gages. Accordingly, provision has been made for the gage member which contacts with the inner edge of the forepart of the shoe, for example the gage member 82 in the illustrated machine, to travel a greater distance than the gage member 84 which contacts with the outer edge. Such variation of travel of the two gage members in the illustrated machine is accomplished by providing gear segments of different pitch diameters. In the illustrated machine the pitch diameter of the gear segment 98 about the axis of the pin 88 is substantially one third as great as the pitch diameter of the gear segment 96 about the axis of the pin 92. Assuming that the gage members 82 and 84 have been adjusted by turning the head 110 to position properly a sole of a given size, it will be apparent that when a larger sized sole of the same style is inserted between the gage members the gage member 82 will travel substantially three times as far as the gage member 84. The result will be that the larger sized sole will still be properly centered in relation to the matrix roll without any need of readjusting the gage members by turning the head 110.

As previously stated, the bearing blocks 18 of the matrix roll shaft are slidably mounted for vertical adjustment in the forks 20. Such adjustment is effected by wedge blocks 152 (Fig. 1), a pair of which are provided to bear against the top of each of the bearing blocks 18. The bearing blocks 18 are urged upwardly against the wedge blocks 152 by springs (not shown). The wedge blocks 152 are forced downwardly or released upwardly to obtain a desired setting of the matrix roll relatively to the skiving knife and the feed roll by a mechanism similar to that disclosed in the above-mentioned Letters Patent No. 1,382,689. This mechanism is operated by a hand wheel 154 (Fig. 3) by which the adjustment is effected.

The hand wheel 154 of the illustrated machine has formed in its periphery a groove 156, in which is slidably mounted a split ring 158 of resilient metal which may readily be sprung into the groove. The groove is annular and concentric with the axis of the wheel. The ring 158 bears scale markings 160 which cooperate with a pointer 162 fixed upon the machine frame to indicate a desired adjustment of the matrix roll. Knobs 164 extend from the ring 158 adjacent to its ends to facilitate turning the ring by sliding it in the groove relatively to the hand wheel 154. The ring 158 grips the bottom of the groove with sufficient friction to hold it against accidental slipping; the friction is not great enough, however, to prevent the operator from turning the ring easily.

When a batch of soles of the same style but of different sizes are to be skived, the operator inserts a sole of the largest size between the centering gages and then, without reference to the scale markings, adjusts the matrix roll upwardly or downwardly, by turning the hand wheel 154, to a position such as will enable a skiving cut of proper depth to be made for that sole. Then, without moving the hand wheel, he turns the ring 158 until the scale marking corresponding to the size of that particular sole registers with the pointer 162. The scale markings may thereafter be relied upon to indicate proper adjustments for all sizes of that style. Whenever a batch of soles of a different style are to be operated upon, the ring 158 is similarly shifted to give proper indications for the various sizes of that particular style.

Having described my invention, what I claim as new and desire to secure by Letters Patent of the United States is:

1. A gaging mechanism comprising a pair of gage members, a pivotal mounting for each of said gage members, and a gear secured to each of said gage members, said gears being in mesh with each other, and one of said gears having a greater pitch diameter than the other, whereby a movement of one of said gage members about its pivotal mounting will cause a greater or less movement of the other gage member.

2. A gaging mechanism comprising a pair of gage members adapted to receive a work piece between them, a pivotal mounting for each of said gage members, resilient means for urging each of said gage members toward the other, and a gear segment secured to each of said gage members, said gear segments being in mesh with each other, and one of said gear segments having a greater pitch diameter than the other, whereby the mid-point between the gage members will be displaced in accordance with the degree of separation of the gage members when a work piece is inserted between them.

3. A gaging mechanism comprising a pair of gage members, a pivotal mounting for each of said gage members, a gear secured to one of said gage members, a gear rotatable about the pivotal mounting of the other gage member, and means for securing the second mentioned gear to the other gage member, said securing means being constructed and arranged for adjustment of the angular positions of the gear and the gage member relatively to each other about the pivotal mounting.

4. A gaging mechanism constructed and arranged to receive a work piece between them, a pivotal mounting for each of said gage members, resilient means for urging said gage members toward each other, a gear segment secured to one of said gage members, a gear segment fulcrumed about the pivotal mounting of the other gage member, and means for securing the second mentioned gear segment to the other gage member, said securing means being constructed and arranged for adjustment relatively to each other of the angular positions of the gear segment and the gage member about the pivotal mounting to enable the mid-point between the gage members to be varied.

5. In combination, a pair of rolls constructed and arranged to engage opposite sides of a work piece, and a gage extending partially around one of said rolls and having portions adapted to engage the edge of the work piece forwardly and rearwardly respectively of the bite of said rolls.

6. In combination, a pair of rolls constructed and arranged to engage opposite sides of a work piece, and a gage pivotally mounted on one side of the bite of said rolls and extending partially around one of said rolls, said gage having a portion adapted to engage the edge of the work piece on the opposite side of the bite of said rolls.

40 7. In combination, a pair of rolls constructed and arranged to engage opposite sides of a work piece, and a pair of gages each pivotally mounted on the same side of the bite of said rolls for engaging opposite edges respectively of a work piece, each of said gages extending partially around one of said rolls and having work-engaging faces located on opposite sides respectively of the bite of said rolls.

50 8. A machine for operating upon soles having, in combination, a roll engageable with a surface of a sole, means for supporting a sole against said roll, and a pair of centering gages for engaging opposite edges respectively of a sole, each of said gages extending partially around said roll and having a work engaging face on each side of said roll.

60 9. A machine for operating upon soles, having in combination, a roll engageable with a surface of a sole, means for supporting a sole against said roll, a pair of centering gages for engaging opposite edges respectively of a sole, each of said gages extending partially around said roll and having a work-engaging face on each side of said roll, pivotally mounted arms upon which said gages

are supported, and means for holding said gages with their work-engaging faces in parallel relation in all positions of said arms.

10. A machine for skiving sole edges comprising a matrix roll, a feed roll adapted to support a sole against said matrix roll, a skiving knife having its edge positioned close to the bite of said rolls, and a pair of centering gages for engaging opposite edges respectively of the sole, each of said gages extending partially around said matrix roll and having a work-engaging face on each side of said matrix roll.

15 11. A machine for skiving sole edges, comprising a matrix roll, a feed roll adapted to support a sole against said matrix roll, a skiving knife having its edge positioned close to the bite of said rolls, a pair of centering gages for engaging opposite edges respectively of the sole, said gages extending close to the bite of said rolls, and an extension detachably secured to each of said gages 20 and extending partially around said matrix roll to control the position of a sole at a locality beyond the matrix roll.

25 12. A machine for skiving sole edges, comprising a matrix roll, a feed roll adapted to support a sole against said matrix roll, a skiving knife having its edge positioned close to the bite of said rolls, a pair of centering gages for engaging opposite edges respectively of the forepart of a sole, 30 a pair of centering gages for engaging opposite edges respectively of the rear portion of the sole, and means for adjusting a gage member of one pair independently of the other gage member of that pair to vary the common center line of that pair of gages.

35 13. A machine for skiving sole edges, comprising a matrix roll, sole feeding means constructed and arranged to support a sole against said matrix roll, a skiving knife in operative relation to said matrix roll and said feeding means, and 40 means for adjusting the position of said matrix roll relatively to said skiving knife, said adjusting means including a hand wheel, a fixed pointer, and a member having scale markings which co-operate with said pointer to indicate the adjustment of said matrix roll for various sizes of soles, 45 said indicating member being adjustably mounted upon said hand wheel to enable the scale markings to indicate proper size adjustments of the matrix roll for soles of various styles.

50 14. In a machine for skiving sole edges, skiving means, means for adjusting said skiving means to accommodate soles of varying sizes, and means for indicating the proper setting of said adjusting means according to the size of the soles to be skived, said indicating means being adjustable to enable different settings of said adjusting means to be obtained for a single size indication, thereby facilitating the adjustment of the skiving means 55 for operations upon soles which are of different styles and which, by reason of the differences of style, require different settings of the adjusting means for the same size of sole.

CHARLES E. HOOD.
